MILTON E. KREIDLER, OF YAKIMA, WASHINGTON, ASSIGNOR OF ONE-HALF TO J. C. DOBRIN, OF YAKIMA, WASHINGTON.

BED FRAME.

Application filed November 16, 1925. Serial No. 69,299.

My invention relates to improvements in folding collapsible bed frames of the form that are adapted to be carried on automobiles and the object of my invention is to 5 provide a collapsible bed frame of simple and substantial construction that is rigid and strong when extended and that is capable of being folded into a very small and compact package when not in use.

10 Another object is to provide a collapsible bed frame in which all of the parts are pivotally connected so that they may be folded in normally horizontal direction and to provide a bed frame which has a box or container fastened directly thereto, one part of the box being secured to the head and the other part of the box being secured to the foot of the bed frame.

15 A further object is to provide simple and efficient means for tightening the bed supporting member or web on the bed frame.

I accomplish these objects by devices illustrated in the accompanying drawings, wherein—

20 Figure 1 is a plan view of a bed frame constructed in accordance with my invention as the same may appear when extended ready for use, the cover of the box at one end of the bed frame being shown in an 25 open position;

Fig. 2 is a view in side elevation of the bed frame in extended position;

Fig. 3 is a view in end elevation of the box as it may appear when the bed frame is 30 folded therein;

Fig. 4 is a sectional view of the box substantially on broken line 4, 4 of Fig. 3 showing the bed frame folded, the spring and web portion that supports the mattress being omitted;

Fig. 5 is a fragmentary sectional view on a larger scale showing the means for tightening the mattress supporting web.

Referring to the drawings, throughout 45 which like reference numerals indicate like parts, I show a bed frame comprising in part two opposite end bars 6 and 7. The bar 6 is provided at one end with a short rigidly connected side piece 8 that extends at right 50 angles therefrom and at the other end with a longer rigidly connected side 9 extending at right angles therefrom. In a similar manner the end bar 7 is provided at opposite ends with a shorter and a longer side

piece 10 and 11 respectively that extend at 55 right angles therefrom, the shorter side piece 10 of the end bar 6 being opposite the longer side piece 9 of the end bar 7 when the bed frame is assembled.

Two side members, formed of parts, 12, 13, 14 and 15 serve to connect the end bars 6 and 7 and hold the same in spaced relation, said side members being connected with the respective side pieces 8, 11, 9 and 10 of the end bars by pivot bolts 16 which 60 are normally vertical.

The members 12 and 13 are of equal length and are pivotally connected midway between the two ends of the bed by a vertical pivot bolt 17 that is offset to the outside 70 of said members to better facilitate the folding of the same. The members 14 and 15 are similarly connected by a vertical pivot bolt 18. The side members are all provided at the locations of the pivots 17 and 18 with 75 hub portions 20 which preferably have toothed or serrated surfaces 21 in contact with each other to prevent relative movement of the side members when the nuts are tightened on the bolts 17 and 18. As a 80 further means for making the side bars rigid I provide, on the bottoms of the members 13 and 14, thin flat plate portions 22, only one of which is shown, that underlie the ends of the respective members 12 and 15 85 and have notches 23 in their ends for the reception of bolts 24 that are slidably disposed in slots 25 in the members 12 and 15.

When the bolts 24 are moved toward the ends of the slots 25 away from pivots 17 90 and 18 the end plates 22 are released. When the side members 12, 13, 14 and 15 are in the extended position and the bolts 24 are moved toward the pivots 17 and 18, said bolts 24 enter the notches 23 and, when the nuts are 95 tightened thereon the members 12 and 13 on one side and the members 14 and 15 on the other side are rigidly held in extended relation to form two rigid and non-yielding side bars.

The bed frame may be supported on legs 26 that are pivoted to the frame and arranged to be held in extended positions by folding angle braces 27.

A container or box for the bed is formed 105 of two halves or sections 28 and 29 secured as by bolts 30 to the respective end bars 6 and 7. A cover 31 is hinged to one of the

box sections 28 and the two sections 28 and 29 are adapted to be secured together by hooks 32.

A mattress supporting web 33 which may be formed of flexible and easily folded cables is connected at one end with springs 34 that are secured to end bar 7 and at the other end with other springs 35 that are connected with short cables 36 that are secured to and adapted to be wound on a roller 37 which extends crosswise within the end bar 6. Roller 37 is provided at one end with a ratchet wheel 38 arranged to be held against unwinding movement of the roller by a pawl 39. The outwardly protruding square end 40 of roller 37 is arranged to be engaged by a crank 41, shown dotted in Fig. 1, for turning the roller to properly tension the web 33.

When the bed is extended the several parts occupy the positions shown in Figs. 1 and 2, in which position the bed frame is ready for the reception of the bed clothing. When the bed is to be folded the nuts on bolts 24 may be loosened and said bolts 24 moved to the ends of slots 25 furthest from pivots 17 and 18 thus releasing plates 22. The nuts on pivot bolts 17 and 18 may then be loosened and the side bars 12, 13, 14 and 15 folded inwardly so that the side bar 12 lies adjacent to the end piece 6 and side bar 15 lies adjacent to the end bar 7 as shown in Fig. 4, while the side bars are being folded the web is lifted up so that when the side bars are fully folded within the box the web may lie on top of the same. The web is omitted from the drawing in Fig. 4. Before the side bars are fully folded the legs and leg braces are folded along side of, or within the side bars.

The difference in length of the respective side members 8 and 9 at one end and 10 and 11 at the other end are important in locating the pivots 16 closer to or farther away from

the end bars 6 and 7 so that the side bars will fold compactly side by side. The side bars are pivoted to fold in a horizontal plane thus making the folded bed frame very compact. In practice I find that the bed will fold nicely within a box that is not more than twelve inches wide and five inches deep and that may be very conveniently carried on the running board of an automobile. The side and end bars of which the bed frame is formed may be entirely of metal or they may be made chiefly of wood with the pivot portions formed of metal.

Before folding the bed the web 33 may be slackened, if desired, by releasing the ratchet means on the roller 37 and after opening out or extending the bed frame the ratchet means may be wound up to tighten the web 33.

The foregoing description and accompanying drawings clearly disclose a preferred embodiment of my invention but it will be understood that this disclosure is merely illustrative and that changes may be resorted to within the scope and spirit of the following claims:

What I claim is:

In a folding bed frame of the class described, a side bar formed of two sections having overlapping ends provided with interfitting serrated hubs, one of said ends having a longitudinally extending slot, a projecting plate portion on the other end provided with a notch arranged to register with said slot when said two sections are extended in prolongation of each other, a pivot bolt passing through said hubs and another bolt movable within said slot into and out of engagement with said notch.

In witness whereof I hereunto subscribe my name this 24th day of October A. D. 1925.

MILTON E. KREIDLER.
